UNITED STATES PATENT OFFICE.

NELS T. NELSON, OF ATTLEBORO, MASSACHUSETTS, ASSIGNOR TO J. F. STURDY'S SONS CO., OF ATTLEBORO FALLS, MASSACHUSETTS, A CORPORATION OF MASSACHUSETTS.

BRACELET END HOOK.

Application filed May 20, 1927. Serial No. 192,915.

This invention relates to a bracelet end hook of the type secured to the ends of an ornamental link chain to attach the same to the bails or lugs of a wrist watch, and this invention has for its object to provide in such a construction a pivoted hook closing tongue which has portions readily accessible for manually swinging the tongue on its pivot to permit the hook to engage or be disengaged from the bail of a wrist watch.

A still further object of the invention is to provide a pivoted tongue having a portion extending along the outer surface of the back wall of the body portion of the end hook with wings for gripping the side walls of the hook to retain the tongue in closed position.

A still further object of the invention is to so pivot the tongue that the pivot pin will be prevented from endways movement by the side walls of the hook thus eliminating the necessity of enlarging the ends of the pin for this purpose.

The invention further consists in the provision of ears on the back wall and also integral ears on the tongue through which the pivot pin passes to mount the tongue in its operative position.

With these and other objects in view, the invention consists of certain novel features of construction, as will be more fully described, and particularly pointed out in the appended claims.

In the accompanying drawings:

Figure 1 is a perspective view illustrating the hook as attaching one of the ends of the flexible bracelet to the bail of a wrist watch and showing in dotted lines the position of the tongue when swung on its pivot to permit disengagement of the hook from the bail.

Figure 2 is a perspective view of the body portion of the hook with the back wall before being folded into finished position.

Figure 3 is a perspective view of the tongue.

Figure 4 is a perspective view of the pivot pin.

Figure 5 is a sectional side view showing the tongue as mounted on the back wall just before the back wall is folded to its final position.

Figure 6 is a sectional view similar to Figure 5 showing the back wall folded to its closed position.

Figure 7 is a section on line 7—7 of Figure 6.

Figure 8 is a section on line 8—8 of Figure 6.

Figure 9 is a central sectional side view of the tongue in open position illustrating in dotted lines the bails or lugs of a wrist watch entering the opening of the hook.

Figure 10 is a side elevation of the hook portion of the watch showing the tongue in the position that it assumes when the hook is being detached from the watch bails.

It is found in practice desirable to provide a hook for attaching a watch bracelet to the bails of a wrist watch with a pivoted hook closing tongue which may be easily manipulated for attaching or detaching purposes and yet one which will be retained in its closed position and prevent inadvertent or accidental opening to permit detachment of the watch therefrom. It is further found of advantage to provide such a construction which is strong and durable and so constructed that the same may be formed by the minimum number of hand operations and to accomplish this I have pivoted a tongue on the back wall of the body of the hook with a pivot pin so located that it is prevented from endwise movement by the side walls of the body of the hook, thus eliminating the necessity of enlarging the heads of the pivot pin to hold the same against endways movement and further, I have so mounted this tongue that no springs are necessary for its operation, it being held in closed position by frictional engagement with the side walls of the body of the hook and the following is a detailed description of the present embodiment of this invention and illustrating one construction by which these advantageous results may be accomplished:

With reference to the drawings, 10 designates the top wall of the body portion of the end hook which is provided with side walls 11 and a back wall 12 formed by folding an extended portion of the top wall back upon itself, as illustrated in Figure 5, the hook proper is also formed by extending the top wall and folding it into a hook 13 to receive the bail 14 of a wrist watch 15. In order to close the opening 16 of the hook, I have pivotally mounted a tongue 17 which has integral ears 18 cut and bent from the stock

of the tongue with piercings 19 to receive the pivot pin 22 which also passes through ears 20 carried by the back wall 12 to pivotally mount the tongue in position in the body.

5 The pivot pin 22 is positioned through both ears 18 on the tongue and 20 on the back wall before the back wall 12 is folded into final position as illustrated in Figure 6 and this pin being of substantially the length 10 of the distance between the side walls is retained and prevented from endways movement when the back wall 12 with the tongue 17 pivoted thereon is folded into its final operating position, as illustrated in Figure 6.

15 After the back wall is folded to final position the edges 23 of the side walls 11 are folded slightly over the back wall to retain it in finished position. One end of the tongue 24 engages beneath the end of the hook 13 to close the opening 16 thereto and the opposite end 25 of this tongue extends along the outer surface of the back wall 12 and has wings 26 to frictionally engage the outer surface of the side walls 12 with portions 20 of the stock 27 deflected outwardly to form knobs to be manually engaged for swinging the tongue on its pivot to open the hook.

30 The deflection of the sheet stock to form knobs causes recesses 28 on the inner surface of the wings which receive the detents 29 pressed outwardly from the side walls 11 and thus the tongue is securely frictionally retained in its closed position by the snapping 35 of the wings 26 over the detents 29.

In doubling the portion or back wall 12 back upon itself an opening or loop 30 is formed to receive one of the connecting links of the bracelet 31, as illustrated in 40 Figure 1.

I have provided a hook which is strong and durable in its construction and one which may be made with the minimum hand work to reduce its cost of production.

45 The foregoing description is directed solely towards the construction illustrated, but I desire it to be understood that I reserve the privilege of resorting to all the mechanical changes to which the device is 50 susceptible, the invention being defined and limited only by the terms of the appended claims.

I claim:

1. A bracelet end hook comprising a body 55 having front, back and side walls, the front wall being extended and formed into a hook, a tongue pivoted in said body intermediate its ends and of a length to have one end close said hook, the opposite end of the tongue extending along said back wall with portions 60 engaging the outer surface of said side walls to be manually grasped to swing said tongue on its pivot to open said hook.

2. A bracelet end hook comprising a body 65 having front, back and side walls, the front

wall being extended and formed into a hook, a tongue pivoted in said body intermediate its ends and of a length to have one end close said hook, the opposite end of the tongue extending along said back wall with 70 portions engaging the outer surface of said side walls to be manually grasped to swing said tongue on its pivot to open said hook and means between said tongue and side wall for frictionally retaining said tongue in 75 closed position.

3. A bracelet end hook comprising a body having front, back and side walls the front wall being extended and formed into hook shape, a tongue pivoted in said body positioned to close said hook and having a portion extending along said back wall with wings extending along the side wall of the body on the outer surface thereof when the hook is in closed position, detents on said side walls and recesses in said wings to receive said detents when the wings are snapped thereover to hold the tongue in closed position.

4. A bracelet end hook comprising a body 80 having top, bottom and side walls with said top wall extended and formed into a hook, a tongue pivoted in said body in position to close the opening to said hook and having a portion extending along the outer surface of said side walls to be manually engaged to operate said tongue.

5. A bracelet end hook comprising a body having top, bottom and side walls with the top wall extended and formed into a hook, 85 a tongue for closing the opening to said hook, and a pivot pin extending through portions of said tongue and body and so positioned as to be prevented from endways movement by said side walls.

6. A bracelet end hook comprising a body having top, bottom and side walls with the top wall extended and formed into a hook, a tongue for closing the opening to said hook, 90 ears on said tongue and on said back wall, a pivot pin extending through said ears to pivotally mount said tongue on said back wall, said pin being located between said side walls when the back wall is in working position whereby to prevent endways movement 95 of the pin without enlarging its heads.

7. A bracelet end hook comprising a body having a front wall formed into hook shape at one end and folded upon itself at the opposite end to form a back wall, side walls carried by the front wall to close the space between the front and back walls, a pair of ears having pivot openings therethrough carried by the back wall and located between said side walls and extending toward said front wall, a tongue having portions cut from its stock and bent to form a pair of ears with pivot openings therein, a pivot pin of a length substantially the distance between said side walls extending through the 100

openings in the ears of both pairs to pivotally mount the tongue in the body in position to close the opening of said hook-shaped end, wings on said tongue extending along the outer surface of said side walls when the tongue is in closing position, a portion of the stock of said wings being deflected out-

wardly to form finger engaging knobs, detents on said side walls to be received in said deflected knobs and over which said wings 10 may snap with resilient frictional engagement to hold said tongue in closed position.

In testimony whereof I affix my signature.
NELS T. NELSON.
